UNITED STATES PATENT OFFICE.

GEORGE M. LANE, OF NEWARK, NEW JERSEY.

ELECTRIC-ARC LAMP.

SPECIFICATION forming part of Letters Patent No. 678,576, dated July 16, 1901.

Application filed November 14, 1900. Serial No. 36,522. (No model.)

To all whom it may concern:

Be it known that I, GEORGE M. LANE, a citizen of the United States, residing at Newark, in the county of Essex and State of New Jersey, have invented certain new and useful Improvements in Arc-Lamps; and I do hereby declare the following to be a full, clear, and exact description of the invention, such as will enable others skilled in the art to which it appertains to make and use the same.

This invention has relation to electric-arc lamps, and aims to provide a simple, effective, and long-lived device of this character in which the electrodes and the feeding, controlling, and cut-out mechanisms are inclosed in a vacuum and protected from atmospheric influences, with the result of a better light and a slower consumption of the carbon pencils.

The invention also consists of the novel features, details of construction, and combination of the parts, which hereinafter will be more fully disclosed and finally claimed, and for this purpose, and also to acquire a knowledge of the merits of the invention and the structural details of the means whereby the results are attained, reference is to be had to the appended description and drawings hereto attached.

While the essential and characteristic features of the invention are necessarily susceptible of modification, still the preferred embodiment of the invention is illustrated in the accompanying drawings, in which—

Figure 1 is a side elevation of an arc-lamp of the shunt type embodying the invention, the casing being in section to disclose the feeding and cut-out mechanisms and their relative position when the lamp is trimmed and prior to the passage of the current. Fig. 2 is a diagrammatical view showing the circuits when the lamp is burning. Fig. 3 is a view similar to Fig. 1 of an arc-lamp of the differential type. Fig. 4 is a diagram showing the circuit when the lamp is burning. Fig. 5 is an enlarged section of the valve. Fig. 6 is a detail view of the compound cut-out lever, the parts being separated. Fig. 7 is a top plan view of the cut-out lever with the parts connected. Fig. 8 shows a modification of the shunt type of lamp. Fig. 9

shows a modification of the differential form of lamp.

Corresponding and like parts are referred to in the following description and indicated in all the views of the drawings by the same reference characters.

The lamp may be either of the shunt type or the differential variety, both being illustrated to demonstrate the application of the invention in connection therewith. The cut-out, controlling, and feeding mechanisms are housed in any selected way, the housing 1 in the present instance being tightly closed, so as to facilitate the formation of a vacuum therein. The globe 2 is attached to the housing or frame 1 in any desired way, preferably by means of screw-thread, the joint being such as to prevent the passage of air when a vacuum is created therein. A valve 3 is provided to facilitate the creation of a vacuum within the globe and frame and may be of any construction. As shown, the valve consists of a tube 4, having a valve-seat 5 at its outer end, normally closed by a flap-valve 6, adapted to open outwardly and normally held closed by a spring 7, secured at one end to the tube 4 and having its opposite end bent and pressing inwardly upon the valve 6. When a vacuum is created within the globe and frame, the valve 6 is held seated by atmospheric pressure and is free to open outward to relieve the globe of any internal pressure in excess of the atmospheric pressure, so as to prevent destruction of the globe if no vent were provided. The valve 6 and adjuncts constitute a safety-valve and may be located in any desired or convenient position, so long as an automatic vent is provided to relieve the globe of abnormal internal pressure. A tube 8 projects from the tube 4 and is in communication therewith, and the outer portion of its bore is enlarged to receive a spring-actuated valve 9, which is adapted to open outwardly when exhausting the air from the globe and which closes to prevent ingress of air. A cap 10 is fitted to the outer end of the tube 8 and when removed admits of an air-pump or other vacuum-creating means being applied to the tube 8 when it is desired to exhaust the air from the globe. By having

the valves juxtaposed, as illustrated, a simple and economical construction results and the tube 4 forms a body for each of the valves and but one point of connection of the valves with the lamp is necessary.

- 5 The lower electrode or carbon pencil 11 is supported by means of an arm 12, pendent from the frame, and the upper electrode or carbon pencil 13 is slidably mounted in a tubular extension 14 of the frame in the ordinary manner and may be controlled by any feeding mechanism, either of the clutch type, as illustrated, or a train of gearing, as commonly provided in devices of this character.
- 10 15 The clutch-lever 15 is mounted upon a rocker-bearing 16, which admits of a bodily longitudinal movement of said lever, whereby the best results are obtained in the feed of the pencil when the lamp is in operation. A link 20 25 30 connects the clutch-lever 15 with the vibrating beam or frame 18, which carries the armatures 19 and 20, coöperating with, respectively, the main and shunt magnets 21 and 22. These magnets 21 and 22 may be 35 40 45 disposed either upon the same or opposite sides of the pulsating lever, according to the arrangement of the vitals of the lamp. The binding-post 23 represents the positive pole and is electrically connected with the frame 50 55 or housing of the lamp, and the binding-post 24 constitutes the negative pole and is electrically insulated from the frame or housing. The terminals of the shunt-helix are connected with the poles 23 and 24. The cut-out 60 65 magnet 25 has one end of its wire connected with the pole 24 and the opposite end connected with the lower pencil or electrode 11 and when energized attracts the armature 26 and releases or opens the cut-out, which consists of an electric contact 27 and a pivoted arm 28. The contact 27 is electrically insulated from the frame or housing of the lamp and constitutes one terminal of the wire of the main magnet 21, the other terminal being 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 electrodes 11 and 13 are separated and the arc is established and the feed of the carbon pencils is controlled by the shunt-magnet 22 and the main magnet 21 in the well-known manner. When the arc lengthens to an abnormal degree, the armature 20 is attracted by the magnet 22 to such an extent as to lift the outer end of the cut-out lever 28 and bring it into electrical contact with the part 27, thereby short-circuiting the lamp and cutting it out of action.

The lamp illustrated in Fig. 8 is the same in action as that shown in Figs. 1 and 2 and involves a simpler construction in that the shunt and main magnets are coaxially arranged, being wound upon the same spool.

The differential form of lamp (shown in Fig. 9) has the magnets 21 and 22 placed one above the other, with the electrode 13 passing through them and the hollow armatures 19 and 20 and operates in the same manner as the construction shown in Figs 3 and 4.

Having thus described the invention, what is claimed as new is—

1. In an electric-arc lamp, and in combination with the electrodes, feeding mechanism therefor, and a magnet-controlled vibrating lever for actuating the feeding mechanism, a cut-out magnet, a fixed contact, a lever bearing an armature to coöperate with the cut-out magnet, and an arm pivoted to the said lever carrying the armature of the cut-out magnet and movable with the said lever in one direction and adapted to have independent movement thereof in the opposite

direction when influenced by the aforementioned vibrating lever to cut the lamp out of circuit, substantially as set forth.

2. In an electric-arc lamp, and in combination with the electrodes, feeding mechanism therefor, and a magnet-controlled vibrating lever for actuating the feeding mechanism, a cut-out magnet, a cut-out lever bearing an armature and coöperating with the said cut-out magnet, an arm pivoted to the cut-out lever and free to have movement in one direction, coöperating stops between the pivoted arm and the cut-out lever to cause the two to move together in the opposite direction, and a fixed contact in the path of the said pivoted arm, the parts being combined to cut the lamp out of circuit under abnormal conditions, substantially as specified.

3. In an electric-arc lamp, and in combination with the vacuum-inclosure for the electrodes, a tube constituting a valve-body, and having a lateral tubular extension in communication with the bore thereof; a safety-valve applied to the outer end of said tube to relieve the vacuum-inclosure of abnormal internal pressure, and a second valve fitted to the said lateral extension and adapted to co-operate with the vacuum-creating means, substantially as set forth.

In testimony whereof I affix my signature in presence of two witnesses.

GEORGE M. LANE. [L. S.]

Witnesses:

PETER HASSINGER,
PERCY J. BUTTERWORTH.
